(57) **CLAIM**

The ornamental design for a can stacking device, as shown and described.

DESCRIPTION

FIG. 1 shows a perspective view of a can stacking device; FIG. 2 shows a top plan view of the can stacking device; FIG. 3 shows a bottom plan view of the can stacking device; FIG. 4 shows a left side view of the can stacking device; FIG. 5 shows a right side view of the can stacking device; FIG. 6 shows a front view of the can stacking device; and, FIG. 7 shows a rear view of the can stacking device. The broken lines shown in the Figures show portions of the can stacking device which form no part of the claimed design.

1 Claim, 5 Drawing Sheets
